UNITED STATES PATENT OFFICE.

WALTER GREEN, OF WILLISTON, SOUTH CAROLINA.

KNOT-ACTUATED STOP FOR KNITTING-MACHINES.

SPECIFICATION forming part of Letters Patent No. 657,410, dated September 4, 1900.

Application filed February 27, 1900. Serial No. 6,739. (No model.)

To all whom it may concern:

Be it known that I, WALTER GREEN, a citizen of the United States, and a resident of Williston, in the county of Barnwell and State 5 of South Carolina, have invented certain new and useful Improvements in Knot-Actuated Stops for Knitting-Machines, of which the following is a specification.

This invention relates to means which may 10 be arranged in such relation to a knitting-machine that, when a knot, snarl, tangle, or the like passes from the spool it will engage the device forming the subject-matter of my invention and actuate the same to 15 bring the knitting-machine to a stop before the knot or the like has had an opportunity to reach the needles.

My invention is designed more particularly 20 for attachment to the class of knitting-machines which employ a stop-motion for arresting the machine when the work advances to a certain stage, my invention being preferably made to actuate said stop-motion as 25 a result of the passage of the knot in the same manner as if the work had proceeded to a point where the machine is arrested in the normal operation.

To these ends my invention consists in a 30 gravitating weight held normally suspended by the engagement of a lug or projection with a fixed point, a thrust-rod for dislodging the lug or projection to permit the weight to descend, and a suitable fulcrumed lever to which the thrust-rod is attached and which 35 projects into the path of the thread or yarn and constructed at its upper end to offer no obstruction to the passage of the latter in its normal condition, but to be engaged by a knot, so that the lever will be moved by the 40 travel of the knot and the arresting-weight released for operation upon the stop-motion.

My invention will be fully understood upon reference to the accompanying drawings, in which—

45 Figure 1 is a front view of a common type of circular-knitting machine to which my invention is applied, and Fig. 2 is a perspective view of my invention detached.

1 represents a circular-knitting machine 50 which is provided with a common type of stop-motion which embodies a vertical rod 2, having radial paddles 3, upon which the weight

employed for drawing down the thread rests when the work progresses to a certain point in order that the machine may be arrested. 55 For the purposes of my present invention I employ an additional paddle 3^a and mount above the same a weight 4, carried by a suspending-rod 5; which is supported through the medium of a lug 6 from a fixed point 7, 60 which may be any suitable portion of the machine or the table upon which the machine rests. Extending from the suspending-rod 5 is a thrust-rod 8, engaging the rod 5 through the medium of the eye 9, Fig. 2, so as to permit the rod 5 to drop when the lug 6 is displaced by the thrust-rod 8. Said rod 8 is hinged at 10 to a lever 11, which is fulcrumed at 12 and projects vertically to the path of the thread or yarn 13, where it is provided 70 with a fork 14, through which the thread or yarn will normally travel without interruption. As soon, however, as a knot or tangle or the like appears in the thread or yarn it will be engaged by the fork 14 and in continuing its motion under the feed of the machine will throw the lever 11 into the position shown in dotted lines in Fig. 1, which motion will dislodge the lug 6 from the fixed point 7 and 75 permit the weight 4 to drop upon the paddle 80 3^a and stop the machine. The knot is released from the fork 14 by the time the latter reaches the dotted position, and the knot may continue a limited distance until the motion of the machine is arrested. There is ample distance, however, between the actuating-point and the point where the machine is arrested to prevent the knot getting into the 85 needles. Hence the object of the invention is fully accomplished, while the feed of the 90 thread is not arrested by the lever 11, which might effect the breaking of the thread. The fork 14 is open at top, so that the relation between it and the thread is re-established the moment the device is set in normal position. 95

A device such as above described is simple in construction, readily applicable to common forms of knitting-machines without change in the construction of the latter, and is entirely effective in arresting the motion of the 100 machine when a knot appears. The advantage of such a device is readily understood from the fact that knots, tangles, or the like upon reaching the needles cause breakage of

the latter, interfere with the uniformity of the work, and involve the loss of much time in restoring the machine to proper condition.

Having thus described my invention, the following is what I claim as new therein and desire to secure by Letters Patent:

1. In combination with the stop-motion of a knitting-machine, a swinging lever projecting into the path of the thread supplied to said knitting-machine, and constructed to be engaged by a knot, tangle or the like, occurring in said thread, a gravitating member suspended detachably above the stop-motion and dropping by gravity upon the latter when released, and a thrust-bar moved longitudinally by the swinging lever and engaging the gravitating member in a direction transverse to its drop, whereby it is dislodged from its point of suspension by the movement of said lever and gravitates independently of the operating means; substantially as herein set forth.

2. The herein-described actuating device for stop-motions, comprising the gravitating weight, means for suspending said weight provided with a lug engaging a fixed point, a thrust-bar for dislodging said lug, and a lever connected with said thrust-bar and projecting into the path of the thread; substantially as set forth.

3. A stop for knitting-machines, comprising a weight, a suspending-bar for said weight provided with a lug for engagement with a fixed point, a thrust-bar having sliding connection with said weight transverse to the line of movement of said bar, and the lever with which said bar is connected; substantially as set forth.

WALTER GREEN.
